UNITED STATES PATENT OFFICE.

FREDERICK BERGMAN, OF CHICAGO, ILLINOIS, ASSIGNOR OF ONE-THIRD TO AMUEL B. SPACH, OF CHICAGO, ILLINOIS.

BLADE-HOLDER.

1,386,757.

Specification of Letters Patent. Patented Aug. 9, 1921.

Application filed October 4, 1919. Serial No. 328,475.

To all whom it may concern:

Be it known that I, FREDERICK BERGMAN, a citizen of the United States, and a resident of Chicago, in the county of Cook and State of Illinois, have invented certain new and useful Improvements in Blade-Holders, of which the following is a description, reference being had to the accompanying drawing, which forms a part of my specification.

10 My invention relates to a holder more especially intended for properly clamping and holding the blades of the knife or sections of the sickle of a reaper or mowing machine, during the operation of sharpening or grinding, which is usually accomplished with a grind-stone mounted to revolve.

The object of my invention is to provide a construction whereby the knife blade or sickle section will be rigidly clamped in place in order to present the knife-edge at the proper angle to the grind-stone or sharpening element; the holder being adjustable so as to provide the proper bevel or edge to the knife-blade and when such adjustment has been accomplished, the operator will be enabled to give all similar knife-blades or sickle sections the same and proper bevel or edge; thus causing the bevel or edge 20 to be uniform, not only throughout the entire edge, but also on the similar side or edge of all corresponding blades or sickle-sections, because of the guiding means or nature of the holder. The invention 25 templates a construction wherein the knife-blades or sickle-sections may be quickly and firmly clamped into place; at the same time enabling the holder to be adjusted so as to present the other edge of the respective 30 knife-blades to the rotating stone or grinder; the objects and advantages of my invention being more readily comprehended from the following detailed description of the drawing, wherein:

45 Figure 1 is a side elevation of my improved holder provided with a knife-blade or sickle-section, shown applied to a section of a grind-stone.

Fig. 2 is a top plan view of the construction as shown in Fig. 1. 50

Fig. 3 is a longitudinal sectional view taken on the line 3—3 of Fig. 2 looking in the direction of the arrows.

Fig. 4 is a cross sectional view taken on the line 4—4 of Fig. 2 looking in the direction of the arrows. 55

Fig. 5 is a detail view of the roller bracket clamping mechanism.

The knife-blade holder, as disclosed, is more especially intended for holding the 60 respective knife-blades or sickle-sections after the same have been removed from the supporting rod or knife-bar of the sickle; the holder being especially adapted for holding the knife-blades or sickle-sections 65 described in a co-pending application, for an improved sickle, filed by me.

In the particular exemplification of the invention as disclosed in the drawing, it comprises the main plate 10 on which the 70 knife-blade or sickle-section 11 rests; and this main plate 10 is provided with a yoke 12 disposed transversely over the top of said main plate 10. The rear end of the main plate 10 is shown provided with a 75 pair of apertures or holes 13 arranged adjacent opposite sides of the plate 10. The holes 13 are adapted to receive a pin or bolt 14 for securing the end of a blade or sickle-section holding member 15 in place. 80 The blade-holding member 15 is normally adapted to rest on the main plate 10 and be disposed lengthwise thereof through the yoke 12; while the latter is provided with suitable means, as for example the set-screws or bolts 16, adapted to screw down onto the holding member 15 and firmly clamp the same in its adjusted position, 85 namely with the forward end of the holding member 15 swung diagonally toward the opposite side of the plate 10 from the side to which the rear end of the holding member is secured by bolt 14; see Fig. 2. The holding member 15, in order to adapt it to the 90 particular type of sickle-section or knife-blade disclosed in my copending application 95

referred to is channeled on its underside for a predetermined portion of the length thereof, as shown at 17 in Fig. 3 for the purpose of receiving the loop or channel formed on 5 or secured to what may be termed the lower side of the knife-blade or sickle-section and indicated at 18. With the channel of the knife-blade inserted into the groove or channel in holding member 15, the upper or bevelled side of the section or knife-blade will be presented downwardly as shown in Fig. 1, permitting it, or rather one of its bevelled edges to be brought into contact with the 10 perimeter or grinding surface of a grinder 15 or stone 19.

The plate 10 and yoke 12 are of such width and the holding member 15 and the bolt-receiving apertures 13 are so correlated, that when the holding member 15 is swung at its 20 forward or blade holding end to the opposite side of the plate 10 from that to which the rear end of the holder is secured, the holding member 15 will be disposed at an angle to the longitudinal center line of plate 10, 25 corresponding with the angle on which the knife-blades or sickle-sections 11 are cut; so that when the knife-blade or section 11 is properly put into place in the holder member 15, one of the sides of the knife-blade or 30 section will be arranged at an acute angle to the holding member 15, and therefore arranged parallel with the main plate 10, see Fig. 2, so as to compel the operator to uniformly present one of the knife-edges or 35 sides of the blade or sickle-section to the grinder or stone 19, and cause a uniform grinding and sharpening of the cutting edges of the respective knife-blades.

In order that the knife-blade or section 40 may be so presented to the grinder or stone 19 as to grind or sharpen the desired portion of the blade or section, I provide a guide which comprises the bar or member 20; the outer end whereof is formed or provided 45 with a head adapted to receive a roller 21 rotatably mounted and adapted to bear against the side of the grinder or stone 19, in the manner shown in Figs. 1 and 2, during the grinding or sharpening operation. The bar 20 is formed to extend into 50 the channel or groove 17 of the holder member 15; or, in the particular exemplification, where the blade or sickle-section 11 is formed with the loop or channel 18, the bar 55 20 is intended to slide through the loop or channel 18 of the respective blades or sections, as shown in Fig. 3. To adjust the guide so as to present the roller 21 at varying distances removed from the forward end 60 of holding member 15, I show the bar 20 provided on its upper side with a slotted plate or fork 22; the slotted plate 22 being secured to the outer end of the bar 20 in any suitable manner, as for example by the rivet 65 23, while the rearwardly disposed portion of

the plate, to-wit the slotted or forked portion thereof, is arranged in spaced relation above the bar 20, a distance commensurate with the thickness of the holding member 15. After the guide roller 21 has been adjusted 70 to the proper distance from the forward end of the holding member 15, the guide or roller is then secured in place against accidental movement by means of the thumb-screw 24 which screws into holder 15, with the shank 75 or threaded portion of the screw disposed through the slotted plate or fork 22, while the flanged head of the screw will firmly clamp the plate or fork 22 into place against any movement lengthwise of holder member 15.

The yoke 12 is shown preferably provided with a pair of set-screws or bolts 16, spaced apart that at least one of the set-screws or bolts 16 will firmly engage with the top of 85 the holding member 15 when the holding member 15 has been swung into either one of the two diagonal positions previously described; that is with the forward end of the holding member 15 swung toward either side 90 of the composite blade-holder; the proper set-screw 16 being then screwed down into firm clamping relation with the holder 15 and preventing any lateral movement of the 95 forward end thereof.

The main plate 10, adjacent what may be termed the rear end thereof, is provided with a pivoted roller-holding bracket 25, pivoted at 26 so as to swing in a direction lengthwise of the holder; with the lower or free end of the bracket 25 provided with a roller 27 which is adapted to engage with the periphery or grinding surface of the stone 19, to determine the proper angularity or positioning of the holder relative to the grinding stone 19. In order to permit the roller-holding bracket 25 to be moved so as to regulate the relation or angularity of the forward end of the holder (and therefore of the blade) relative to the grinding surface or periphery of the stone 19, I provide a slotted arm 28 pivoted at 29 to the bottom of the plate 10, as shown in Fig. 1. The arm 28 is preferably made arcuate as shown and provided with an arcuate slot 30 which is adapted to receive the finger operated screw-rod 31, of a length sufficient to extend through the two apertured lobes 32 formed on the pivoted bracket 25 and therefore also to extend through the arcuate slot 30 of swinging arm 28. The bracket 25 is provided centrally with an elongated opening as shown at 33 for the passage of the arm 28, see Fig. 2, thus enabling the bracket 25 with roller 27 to be swung toward and away from the forward end of the holder and therefore in a direction somewhat lengthwise of the arm 28. The screw-rod 31 is preferably formed at one end so as to enable the same to be operated by hand; while the opposite end is 120 125 130

adapted to receive an ordinary nut 34, which will be prevented from turning by the bracket 25 and will be brought into firm relation with the adjacent apertured lobe 32 on bracket 25 when the screw-rod has been turned so as to effect clamping relation. The screw-rod 31 is preferably provided with collars 35 and 36 loosely mounted on the screw-rod and arranged on opposite sides of the 10 swinging arm 28 and adapted to bear against the adjacent apertured lobe 32. The collar 36 is preferably provided with a reduced extension adapted to pass through the aperture in the adjacent lobe 32 and slightly beyond 15 so as to be engaged by a third collar or ferrule 37 disposed on the screw-rod adjacent to the finger grasping end thereof. With this construction it is evident that when the screw-rod is rotated to screw toward the nut end thereof, the collar or ferrule 37 will be forced into frictional contact with the extended portion of collar 36 and cause the opposite end of the collar 36 to be forced into frictional relation with arm 20 28, with the result that the swinging arm 28 will be firmly clamped between the two collars 35 and 36 and thus maintain the bracket 25 with roller 27 in such adjusted position, that when the roller 27 is placed against the 25 periphery or grinding surface of stone 19, the forward end of the holder will be so disposed or related to the grinding surface of the stone, adjacent the upper side thereof, that the blade in the holder will be properly 30 presented for the desired bevel during the rotation of the stone or sharpening element.

As my improved holder is especially intended for use in connection with sickle-sections or knife-blades of the class hereinbefore referred to, it will be essential to provide a holder which is adapted to present both sharpened or beveled edges of the triangulated blade to the grinding element. After all of the blades to be sharpened have 45 been placed in the holder with one beveled edge presented forwardly, as a result of the forward end of the holding member 15 being swung toward one side of the composite holder, the holding member 15 is then arranged so as to move the forward or blade-holding end thereof toward the opposite side of the holder and thus permit the blades to be so inserted as to present the other edge properly to the grinder element or stone 19; 50 after which the proper set-screw 16 is screwed down onto holder 15 so as to maintain the forward end thereof in its re-adjusted position.

The major portion of the knife-blades or 60 sickle-sections, namely the blades or sections beyond the blades or sections at the inner end of the sickle, are usually of equal thickness and consist of a single member or plate, while the inner end sections or blades are generally provided on the upper surface 65

with a reinforcing triangulated plate extending throughout a major portion of the blade or section. The holder 15, at the forward end thereof, is cut away on the lower side thereof to a depth equal to the thickness 70 of the single piece blades or sections, so that when the blade has been inserted, the rear end of the holding member 15 may be forced down flush with the upper surface of the main plate or body 10, allowing the holder 75 15 to extend in a horizontal plane, that is parallel, throughout its length, with the plate 10. When the inner end sections or blades are inserted into place, the reinforcing plate of these blades will cause the forward end of the holding member 15 to be slightly elevated. In order that the proper angle may be maintained and therefore the proper bevel given to all of the knife-blades or sections, I provide the spacing plate 39. 80 This plate 39 is partially slotted to fit about the bolt 14, see Figs. 2 and 3, while the remainder of the plate is bent upwardly and arranged to fit about the rear end of the holding member 15 so as to enable the proper 85 insertion of the plate 39 into place; the plate 39 being substantially equal in thickness to the thickness of the reinforcing plates which are usually riveted on the upper surface of the inner end sections or blades of the knife 90 or sickle. With the spacing plate 39 put into place as shown in the figures, the rear end of the holding member 15 will be caused to be held in the same spaced relation with the main plate or body 10 as the forward end 95 100 and thus insure the proper presentation of the beveled edges of the respective knife-blades or sections to the grinder or stone 19. As is evident from the construction shown, after the spacing member 39 has been inserted into place, the butterfly nut on bolt 14 may be turned so as to draw the bolt and nut into firm clamping relation with the plate 10 and holding member 15, respectively, thus firmly clamping the spacing 105 member 39 against accidental removal.

While my improved holder is more especially adapted to the sickle-sections or knife-blades herein described, to wit the type disclosed in the copending application referred 110 to, it is apparent that the holder is adapted to hold any removable type of knife-blade or sickle-section intended to be provided with a beveled cutting edge of the nature usually given to the blades or sections of a 115 reaper or mowing machine sickle.

After the holder has been adjusted so as to present one of the beveled edges forwardly, namely with the beveled edge running parallel with the end of the main plate 120 10, and the swinging bracket 25 has been clamped into place by the mechanism previously described so as to adapt the holder to the diameter of the grinder or stone, the operator positions the holder, with the in- 130

serted knife-blade in the manner shown in Fig. 1; placing roller 27 into contact with the grinding surface or periphery of the stone, while the roller 21 is brought into contact with the flat side of the stone. The positioning of the holder as described, causes the blade to be so presented to the grinder or stone that the beveled or cutting edge will be uniformly ground or sharpened throughout the entire beveled edge thereof; and every successively inserted blade will likewise be given the proper and similar bevel or edge.

I have shown and described what I believe to be the simplest and best embodiment of my invention, but the construction may be modified in certain respects without, however, departing from the spirit of the invention.

20 What I claim is:—

1. A holder of the class described, comprising a body portion, a blade-holding member arranged on said body portion and adapted to be disposed in a diagonal manner thereon, means whereby said member may be pivotally secured at one end to said body portion adjacent the sides thereof so as to swing diagonally of the body portion, means whereby the angular position of the blade-holding member may be maintained, and means adjustably secured to the body portion adapted to contact with the grinder or stone at a distance removed from the blade-holding end of the holder whereby the forward blade-holding end of the holder will be presented at the desired angle to the grinder or stone.

2. A blade holder of the character described, comprising a body portion, blade-holding means adapted to be pivotally secured on said body portion, means, adjustably secured to the body portion, adapted to engage with the grinding element or stone whereby the position of the blade relative to the grinding element or stone is controlled, and means, adjustably secured to said blade-holding means, adapted to engage with the side of the stone to prevent movement of the holder and blade transversely of the grinding element or stone beyond a predetermined degree.

3. A holder of the character described, comprising a body portion, blade-holding and clamping means laterally adjustable and adapted to be pivotally secured at one end thereof on the body portion so as to permit the forward end to swing transversely of said body portion and thereby separately present the opposite edges of a triangulated blade to the grinding surface of a grinder or stone, means whereby said first means will be held in its adjusted position, and roller carrying means, adjustably secured to said body portion, adapted to contact with the grinder or stone and thereby control the

bevel to be produced by the grinder or stone on said knife-edges.

4. A holder of the class described, comprising a body portion, a blade-holding member adjustably secured on said body portion so as to swing transversely thereof and in a diagonal manner, a roller-carrying bracket pivotally secured to said body portion so as to permit the roller to engage with the grinding surface or periphery of a grinder or stone when the holder is placed in blade-sharpening position, and means whereby the angularity of said roller-holding bracket to the body-portion may be regulated and the position of the knife-edge relative to the grinder or stone determined.

5. A holder of the class described, comprising a body portion, a blade-holding member adjustably mounted on said body portion so as to be moved into a diagonal position thereon, means whereby the position of said blade-holder may be controlled, a roller-carrying bracket pivotally secured to the body portion at the rear end thereof so as to swing toward or away from the forward end of said roller, while the roller-holding end of said bracket is adapted to come into contact with the grinding surface or periphery of a grinder or stone, and means whereby the positioning of the roller-holding end of said bracket relative to the forward end of the holder may be controlled.

6. A holder of the class described, comprising a body-portion, a blade-holding member adjustably mounted lengthwise on said body-portion and adapted to be moved into a diagonal position on said body-portion, means whereby the member may be held in its adjusted position, blade-clamping means carried by the forward end of said member, an oscillatingly mounted member on said body-portion provided at its free end with an anti-friction member adapted to engage with the surface of the revolving grinder or stone whereby the blades are ground or sharpened, means whereby the oscillatingly mounted member is locked in position and the angularity of the forward end of the blade-holding member relative to the grinding surface of the stone is determined, and adjustable means carried by said blade-holding member adapted to engage with the side of the grind-stone whereby movement of the holder transversely of the grind-stone is limited and the length of the knife-edge to be ground or sharpened is determined.

7. A blade holder of the class described, comprising a body portion, a channeled blade-holding member adjustably secured to said body portion so as to be disposed in a diagonal manner thereon, means whereby the blade may be clamped in said member so as to present its knife-edge in a direction parallel with the front end of said body por-

tion, a guide member adjustably secured to said holding member by said means whereby movement of the holder transversely of the grind-stone may be regulated, a roller-carrying member pivotally secured to the body portion so as to swing toward or away from the forward end of the holder, and clamping means whereby said last member may be secured in position and the angularity of the forward end of the holder relative to the 10 grind-stone regulated.
